PAPER CARRIAGE FOR ACCOUNTING MACHINES

Walter A. Anderson, Bridgeport, Conn., assignor to Underwood Elliott Fisher Company, New York, N. Y., a corporation of Delaware

Application December 30, 1938, Serial No. 248,428

3 Claims. (Cl. 197—126)

This invention relates to paper carriages for accounting machines, and more particularly to means for facilitating carbon printing on checks, short forms and the like.

In printing checks on accounting machines, the general practice is to have the original printing on the check and a carbon printing on the ledger record. However, as the ledger sheet, during its life, is subject to a large amount of handling, the carbon printing thereon often becomes so smeared as to be illegible. It has therefore been found desirable to reverse the printing; that is, to have the original printing on the ledger sheet and the carbon printing on the check. This reversal works to an advantage, as the check receives relatively little handling between the time it is printed and the time it is cancelled.

In adapting the carriage to accommodate this reversal in printing procedure, the problem arises of providing a means for stopping the downward insertion of the check around the platen, so that the writing line of the check is in correct alignment with the printing line of the platen.

Further, since the accounting machine is at times used for work not involving the printing of checks, it is desirable that the stop means above-mentioned, be arranged to be moved to an ineffective position so as to make possible the insertion and adjustment of relatively longer forms.

It is an object of this invention, therefore, to provide a means for holding a sheet or strip of carbon paper in such manner that a ledger or record sheet may be inserted downwardly in front thereof and a check or the like may be readily inserted in back thereof from in front of the platen.

Another object is to provide such a carbon paper holding means that may be readily and easily adjusted to present a fresh writing line of carbon to the printing line of the platen when a formerly used line on the carbon has become worn.

Another object is to provide a simple and effective stop movable to one position where it limits the insertion of a check or short form and thereby allocates it in correct printing alignment with respect to the platen, and to another position where it is ineffective and out of the path of the longer forms used in other types of accounting.

With these and incidental objects in view, the invention consists in certain novel features of construction and combinations of parts, the essential elements of which are set forth in appended claims, and a preferred embodiment of which is hereinafter described with reference to the

drawings which accompany and form part of the specification.

In the drawings:

Figure 1 is a perspective view of a carriage equipped with the present invention,

Figure 2 is a right side elevation showing the improved carbon paper holding means and the movable check stop in effective position, and

Figure 3 is a detail right side view showing the check stop moved to ineffective position.

The invention is illustrated in connection with the type of carriage used on the machine disclosed in Patent No. 2,194,270, issued to Oscar J. Sundstrand on March 19, 1940, and may be readily adapted to the type of carriage disclosed in U. S. Patent No. 2,060,954, issued to Oscar J. Sundstrand on November 17, 1936, or in U. S. Patent No. 2,185,424, issued to Walter A. Anderson on January 2, 1940, or on that disclosed in U. S. application of Walter A. Anderson, Serial No. 92,164, filed July 23, 1936.

Carriage in general

Referring to Figure 1, the carriage is mounted for movement along a track 1. As the carriage moves from right to left, it is stopped in various columnar positions so that type bars (not shown) on the accounting machine may print on the work forms fed around a platen 2. The mechanism for tabulating the carriage from column to column and for returning it to its initial position is disclosed in Patent No. 2,194,270. The carriage is adapted to accommodate both rear fed paper and front fed paper. In the illustration, only front fed paper such as a ledger sheet 3 and a check such as 4 is shown. The platen may be rotated manually by knobs 5 secured to each end of the platen shaft 6, and may be rotated automatically during operations of the machine by suitable feed pawl mechanism (not shown) co-operating with teeth on a ratchet wheel 7 secured to shaft 6. This mechanism is disclosed in Patent No. 2,060,954.

Mechanism for guiding and holding front fed paper

For introducing front fed sheets, a pair of guide chutes 8 and 9 are provided. These chutes are formed with sides 10 which act as edge guides, and are secured on separate brackets 11 mounted for sliding movement along rods 12. The opposite ends of rods 12 are secured by screws, such as 13, to upstanding arms 14, pivoted on semi-cylindrical studs 15 (see also Figure 2). Arms 14 are held in engagement with studs 15 by studs,

such as 16 (Figure 2), secured in the carriage side walls. In operation, this bail structure is swung forwardly from what is known as the closed position shown in Figure 1 to what is known as the open position shown in Figure 2, the paper then inserted, and the bail swung back to the position shown in Figure 1.

After the paper is passed downwardly through the chutes, it is directed under the platen, first by the upper portion of a plate 17 (Figure 2) secured to the frame of the accounting machine. Plate 17 deflects the paper toward a guide which takes the form of a lip 18 secured on a square rod 19 pivoted in the carriage side walls. Movement of the bail to closed position causes the lip to pivot upwardly from the position shown in Figure 2 to a position quite close to the platen, in the manner disclosed in Patent No. 2,185,424. This serves to bend the paper around the platen from a position below the printing point. Pressure rolls 20 are provided to hold the paper firmly against the platen above the printing point.

Mechanism for holding and adjusting carbon paper

Mechanism is provided to hold a sheet or strip of carbon paper 21 along its upper edge, so that its lower end may pass freely around and under the platen in back of ledger sheet 3. This means comprises a pair of forwardly extending arms 22 pivoted on a rod 24* (Figure 2) extending between and secured to the carriage side walls. The rear ends of arms 22 are formed slightly to provide frictional pressure between the arms and the carriage side walls. A pair of parallel transversely extending rods 24 and 25, connected between arms 22 by screws such as 26, provide a support for a carbon paper clamp plate 26*. Plate 26* is pivotally mounted on rod 24 through flanges 27 that extend rearwardly from the plate and have bushings 28 embracing the rod. Weak springs such as 29 (Figure 2), connected between rod 25 and pins such as 30, fixed in the rear side of plate 26*, tension the plate upwardly, causing flanges 27 to bear against rod 25. Collars, such as 31 (Figure 1), secured on rod 24 on the opposite sides of flange 27, prevent lateral displacement of the assembly. A pair of spaced spring clips 32, secured as by screws 33 on the front of plate 26*, are arranged to securely hold the upper edge of the carbon paper 21 between the clip and the plate, the lower free end of the carbon extending downwardly and around the platen as shown in Figures 1 and 2.

By this construction, when the front feed bail is swung from open position (Figure 2) to closed position (Figure 1), causing pressure rolls 20 and the upper ends of chutes 8 and 9 to press against the carbon paper, springs 29 yield to prevent the carbon from being torn. This construction also holds the carbon taut, so that a clear imprint may be made.

It is customary, in present day practice, when using carbon paper, to advance the carbon sheet with the work form when the latter is line spaced, the same sheet of carbon being used over and over for successive work forms until the carbon ceases to give satisfactory impressions. With the present mechanism, however, the carbon is not advanced with the work form (the check), as the latter receives only one line of printing before being removed from the carriage. The carbon, therefore, is kept in one location for successive impressions, until it no longer gives a satisfactory impression. With this method it has been found possible to print thirty or forty

checks before it is necessary to advance the carbon, it then being necessary to advance it only a distance equal to the height of the printed characters.

5 To advance the carbon in this manner, the operator merely pulls the front feed bail to forward position (Figure 2) and raises arms 22 a slight amount about rod 24*. In order that the operator may gauge the amount of upward movement for this line change operation, a pair of outwardly formed nodes 23 are provided on the rear ends of arms 22 and are arranged to frictionally engage a series of corresponding apertures 34 spaced closely together and formed on an arc concentric with the axis 24* in each of the carriage side walls. In changing the line of writing, arms 22 are moved upwardly only an amount sufficient to move the nodes from the apertures in which they are engaged, to the next adjacent set of apertures. Inwardly disposed studs 35, secured in the carriage side walls at the extremities of apertures 34, define the extreme adjustments of arms 22.

Stops for aligning checks, record cards or short forms and the like

As before stated, by having the check or short form inserted in back of the carbon, it is essential that a means be provided for limiting the downward insertion of such forms to align it properly with the printing point, since the presence of the carbon paper in front of the check prevents the operator from doing this visually. This mechanism includes a shaft 36 extending across the entire length of the carriage and supported at its opposite ends in the carriage side walls beneath platen 2. A pair of stops 38, spaced apart and secured to the shaft by screws such as 39 (Figure 2) have upstanding arms 40 which lie in the path of the lower edge of the inserted check or short form 4. When a check is to be inserted, the front feed chute is swung open (Figure 2) and the check is inserted behind the carbon 21 from either side thereof. The check is then passed downwardly between platen 2 and carbon 21, its lower edge following the contour of the carbon and the ledger sheet about the platen until it abuts stops 38. By this means, the checks may be rapidly and easily inserted and removed, each being brought into proper alignment with the platen to insure uniformity in printing.

As before mentioned, since the accounting machine is used also for types of work not involving check printing, and since the forms used in the other types of work are generally of greater length and width than the checks, the stops are adapted to be lowered to a position where they will not interfere with the insertion of these larger forms. To do this, shaft 36 is mounted loosely in the side walls, the left end of the shaft extending through the left side wall and carrying a knob 37 for oscillating the shaft manually. To lower check stops 40 out of the path of the forms, it is only necessary for the operator to oscillate knob 37 a slight extent. An arm 42, secured on shaft 36 near its right hand end, carries a stud 41 that cooperates with a spring detent 43 on the carriage side wall, to limit the extent of oscillation that may be imparted to shaft 36 by knob 37.

In practice, the combination of this adjustable carbon paper holding device, with the stops for aligning short forms or checks, has been found to effect a considerable saving in carbon paper and operating time where the users of the ac-

counting machine desire to have their ledger or record sheets bear the original printing and the checks or short forms bear a carbon imprint.

While the form of mechanism herein shown and described is admirably adapted to fulfill the objects primarily stated, it is to be understood that it is not intended to confine the invention to the one form of embodiment herein disclosed, for it is susceptible of embodiment in various forms, all coming within the scope of the claims which follow.

What is claimed is:

1. In a carbon paper holding means for a paper carriage, arms pivoted on the carriage and connected by rods across their outer ends, a plate pivoted on one of said rods and springs connected between said plate and the other of said rods, said plate carrying a spring clip arranged to engage a sheet of carbon paper.

2. In a carbon paper holding means for a paper carriage having a roller platen, arms pivoted on the carriage and connected by rods across their

outer ends, a plate pivoted on one of said rods and yieldingly connected to the other of said rods, spring clips on said plate for holding a sheet of carbon paper, and means whereby said arms 5 may be adjusted to bring different portions of the carbon paper to the printing line.

3. In a paper carriage of the class described having a roller platen, means above the platen for holding a sheet of carbon paper the lower 10 portion of which loosely encircles the platen, a front feed bail having means for directing paper downwardly in front of the carbon, and movable from an open to a closed position with respect to the platen, said bail in its closed position being arranged to engage and exert a longitudinal tension upon said carbon sheet and yielding means coacting with said holding means to allow the latter to move with the carbon sheet and prevent tearing thereof when the front feed bail 15 is moved from open to closed position.
